LOCKING RING ROLLING MACHINE

Edward C. Kradoska, 1602 Prospect Ave.,
Melrose Park, Pa.

Filed Nov. 20, 1957, Ser. No. 697,590

3 Claims. (Cl. 153—54)

Steel drums are used extensively for storing and transporting various materials, and the open end of one type of these drums is closed by a head which is held in closing position by means of a locking ring which clamps the rim of the head and the rim of the drum together. The locking rings referred to may be tightened and loosened by means of a built-in cam mechanism or by means of a bolt which engages flanges formed at the ends of the ring. The first mentioned type is known as quick lock ring and the second type mentioned is known as bolt lock ring.

The drums and the locking rings are subjected to rough handling and are quickly dented and otherwise deformed.

Because they are expensive, machinery has been devised for de-denting and otherwise re-forming the drums in order to prolong their useful life.

The object of the present invention is to provide an improved apparatus for de-denting and re-forming the locking rings whether they are of the quick lock or of the bolt lock type.

The full nature of the invention will be understood from the following specification and the accompanying drawings in which:

Fig. 1 is a diagrammatic plan view of an apparatus embodying the invention, only such parts being shown as are necessary for understanding of the invention.

Fig. 2 is a section on line 2—2 on Fig. 1.

Fig. 3 is a sectional view taken on line 3—3 of Fig. 2.

Fig. 4 is a sectional view taken on line 4—4 of Fig. 1.

Fig. 5 is a top plan view showing the manner in which the parts yield in a horizontal direction in the presence of a large lateral deformity in order to prevent damage or breakage.

Fig. 6 is similar to Fig. 5 and shows the position which the parts assume in the absence of a large deformity or when a ring has been re-formed to its original and proper shape.

Fig. 7 is a greatly enlarged, fragmentary sectional view showing how the rolls yield in a vertical direction in the presence of a large vertical deformity or when a double thickness portion of the ring is passing between the rolls.

Fig. 8 is similar to Fig. 7 but shows the position of the rolls in the absence of a large vertical deformity or when a single thickness portion of the ring is passing between the rolls.

Fig. 9 is a top plan view of a quick lock ring.

Fig. 10 is a top plan view of a bolt lock ring.

Fig. 11 is a reduced view, partly in section and partly in elevation, of the forming die which supports the ring to be re-rolled, the same being shown with a bolt lock ring mounted thereon.

Fig. 12 is an enlarged, fragmentary view taken on line 12—12 on Fig. 9.

As best shown in Fig. 2, the ring re-rolling apparatus is mounted on front legs 10 and 11 and rear legs 12 and 13, the front legs being somewhat shorter than the rear legs, whereby the apparatus tilts forwardly or toward the operator.

The legs support the platform 14 on which is mounted a reversing motor 16 which is energized, in either direction, in the conventional manner. Motor 16 drives a gear train 18 to rotate shaft 20. Shaft 20 projects above upper platform 22 and carries a forming die 24, the periphery 26 of which supports the ring to be re-rolled in the manner shown in Fig. 11.

The ring to be re-rolled is acted on by two spaced pairs of rolls, one pair being formed of upper and lower rolls 31 and 32, and the other pair being formed of upper and lower rolls 33 and 34. The upper rolls 31 and 33 are carried by stub shafts 36 and 37 which are carried by upper arms 38 and 39 and the lower rolls 32 and 34 are carried by stub shafts 40 and 41 which are carried by lower arms 42 and 43. The upper and lower arms referred to are pivoted at 44 and 45 to connecting straps 46 and are biased toward each other by adjustable springs 48 and 49 which are carried by rods 50 and 51. By adjusting the tension of springs 48 and 49, the pressure of the rolls against the work piece can be controlled. It is to be noted that the pressure of springs 48 and 49 is always such as to permit upper arms 38 and 39 and lower arms 42 and 43 to yield and move to the broken line positions of Fig. 2 whenever the resistance encountered exceeds a given value, so as to guard against damage or breakage which can occur if the arms were rigidly mounted.

Shafts 50 and 51 which carry the upper and lower arms 38 and 39 and 42 and 43, respectively, are carried by a cross member 56 which is pivotally carried by the piston 58 of an air cylinder 60. Cross member 56 is normally retracted to the position shown in Figs. 1 and 2 by springs 62 and is moved toward die 24 or to the position shown in Figs. 5 and 6 by admission of air into cylinder 60 by manipulation of foot valve 64 which is only shown in Fig. 1. Cross member 56 is guided in its movement by means of a pin 68 which engages a slot 70 in a plate 72 which is carried by a portion 74 of the frame of the machine.

The operation is as follows:

40 The ring to be re-rolled, be it of the bolt lock type shown in Figs. 10 and 11, or of the quick lock type, shown in Fig. 9, is clamped on the periphery 26 of die 24, motor 16 is energized and air is admitted into air cylinder 60. The operator, using a switch 76, which is only shown in Fig. 1, causes the motor, and, hence, the die to rotate in opposite directions so as to roll the body of the ring, but to prevent lugs 78 of the rings from passing between the upper and lower rolls. If a ring is badly deformed, as exaggeratedly shown in Fig. 5, plate 56 and the rolls carried thereby will tilt, as diagrammatically shown in Fig. 5 so as to prevent damage or breakage and to permit gradual reforming of the ring. In the absence of a large deformity, or after the ring has been re-formed into its proper shape, the parts will assume the position shown in Fig. 6. In the presence of a small deformity, or of a single thickness portion of the ring, the rolls will assume the position illustrated in Fig. 8 in which the upper and lower rolls are not spread far apart. In the presence of a large deformity, or when a double thickness portion of the ring is encountered, the rolls will be spread further apart, as shown in Fig. 7. It will be understood that the tension of springs 48 and 49 is adjusted according to the work on which the machine is to be used.

65 In practice, I prefer to exert greater spring pressure on one pair of rolls than on the other and to orient the reciprocal rotation of the ring so that it passes between the rolls subjected to the lesser pressure before it passes between the rolls subjected to the greater pressure. For example, I can exert greater spring pressure on rolls 31 and 32 than on rolls 33 and 34, and I place the ring on the die in such a position and I energize the motor so as

to rotate in a direction to cause the ring to pass between rolls 33 and 34 before it passes between rolls 31 and 32. In this way I take advantage of the fact that it takes less force to bend a rod over a large radius than over a small radius. In other words, when a dent or bulge is large, it is more easily re-formed than when it is small, and by the arrangement described, the large bulges are first acted on by the more yielding rolls 33 and 34 and, when the bulges have been somewhat reduced and are more resistant, they are acted on by the less yielding rolls 31 and 32 which complete the elimination of the bulges.

From the foregoing it will be seen that the re-rolling mechanism has a floating mounting so as to have limited rotation about the vertical axis of pin 68 which is parallel to the axis of the work piece; that the rolls are mounted for limited vertical movement in the direction of their vertical axes; that one pair of rolls is subjected to greater compressive pressure, and yields less readily than the other pair and that the ring to be re-rolled passes between the more readily yielding roll before it passes between the less readily yielding rolls.

What I claim is:

1. A machine for reforming a dented locking ring of the type used for clamping a closure to the open end of a drum, said machine including a die rotatable about a vertical axis and on which the ring to be reformed is clamped, a supporting member, means mounting said supporting member for rotation about a vertical axis, a pair of horizontally spaced rollers carried by said supporting member and rotatable about vertical axes, means yieldably biasing said supporting member to a position in which the axes of the rotation of said rollers are equidistant from the axis of rotation of said die, and for yieldably urging said support in the direction of said die, to bring said rollers into contact with a ring clamped on said die with a force sufficient to deform the material of said ring, the tension of said springs being such that, in the presence of resistance of a predetermined value, said

springs will yield and said supporting member tilts to reduce the pressure with which said rollers contact said ring.

2. The structure recited in claim 1 in which said ring has at least one projection extending beyond its external periphery and in which said die is rotated in opposite directions and to an extent less than 360° in each direction to prevent the passage of said projection under said rollers.

3. A machine for reforming a dented locking ring of the type used for clamping a closure to the open end of a drum, said machine including a die rotatable about a vertical axis and on which the ring to be reformed is clamped, a supporting member, means mounting said supporting member for rotation about a vertical axis, a first pair of rollers carried by said supporting member and rotatable about a common vertical axis, yielding means normally biasing said rollers toward each other with a force slightly greater than the force needed to deform the material of said ring, a second pair of rollers carried by said support in horizontally spaced relation to said first pair of rollers and rotatable about a common vertical axis, yielding means biasing said first and second pair of rollers toward each other with a force of a first order whereby, in the presence of resistance in excess of said first order, the rollers forming said pairs will separate, actuating means for yieldably urging said supporting member and said pairs of rollers toward said die to bring said pairs of rollers into contact with said ring with a force of a second order sufficient to deform said ring.
